Inventor:

Hermann Kampes.

UNITED STATES PATENT OFFICE

HERMANN KAMPES, OF ESSEN-RUHR, GERMANY

YIELDING JOINT STRIP FOR THRESHOLDS AND SILLS

Application filed November 20, 1930, Serial No. 496,931, and in Germany November 18, 1929.

The invention relates to a yielding joint strip for the sill or threshold of sash windows or sash doors. The usual way in which sash windows have hitherto been rendered tight is by rebating the sill or threshold as well as the window sash in steps. Therefore the sill of windows and the threshold of doors present projecting members which are awkward. In the case of hospitals for instance it is of great importance that the shocks which operation or sick beds on wheels have imparted to them when passing over such obstacles should be avoided.

Hinged doors with a roller shaped sealing batten or rail let into the threshold and arranged between covering strips and actuated by springs are already known. This arrangement however, possesses the disadvantage, that the roller protrudes above the sill or threshold surface when the door is open; moreover, such a roller could only then fulfill its purpose of a perfect sealing if it could be brought into an effective and accurate contact with the bottom edge of the door, which is practically impossible; then there is the further disadvantage, that the roller must protrude above the threshold and that it is awkward and easy to miss one's footing over it.

The purpose of the invention is to create a sealing off of draught and so on by inserting two covering rails into the sill or weatherboard or threshold, a slot being formed between them into which a strip protrudes, a preferably T-shaped rail, acted upon by a spring closing the slot when the window or door is open, but is in close contact with the strip on its whole length when the window or door is closed.

With this and other objects in view the invention consists in certain novel features of construction, combination and arrangements of parts, which will be hereinafter more fully described and particularly pointed out in the appended claims.

In the accompanying drawing:

Fig. 1 is a vertical cross section of the lower part of a sash door and

Fig. 2 is a corresponding illustration of a sash window.

Fig. 3 is a vertical longitudinal section through the device at two different positions of the lower sash, whereas

Fig. 4 shows a section according to 4—4 of Fig. 1.

The sash door according to Fig. 1 consists of three sashes which can slide in the same manner as sash windows in the guides a^1 , a^2 , a^3 , the sashes b^1 and b^2 being shown. A batten k is provided on the outside of the lower sash b^1 along its lower edge and projects somewhat towards the bottom. A rail or strip c is fixedly attached to the lower rail of the lower sash b^1 . The threshold or weatherboard is provided with a recess d which is partially covered by two parallel rails or strips e . The rail c is free to protrude into the slot formed between the rails e , when the sash b^1 is in its extreme lower position. Pieces of pipes f are let into the masonry at several places below the rails e , these pipe pieces being provided at their top with a large slot f^1 . Within the slot f^1 of all the pipe pieces f a preferably T-shaped rail g is suitably inserted and guided, it being acted upon by spiral or helical springs h arranged within the pipes f . The springs h tend to press the rail g into its extreme top position, in which the bridge g^1 of the rail g seals off the floor. The threshold is step-formed towards the outside so that the batten k seals the interstice or slit between the threshold and sash, as regards the outside, when the door is closed.

The device of the lower sash i of the two sash window shown in Fig. 2 resembles in all its details the above described device.

If the lower sash b^1 or i is pulled down, then it abuts with its strip c on to the bridge g^1 of the rail g , and forces it downwards, at the same time compressing the springs h into the position shown in Figs. 1 and 2 and in the right hand side of Fig. 3. The sash can stably remain by its own weight in this position, or may be locked in this position by means of suitably arranged latches. As soon as the sash b^1 or i is pushed up the rail g follows it until it reaches the extreme upper position shown in the left half of Fig. 3, in which position its surface has reached the

level of the floor or sill. The floor or sill has thus no awkward recesses or projecting battens, but notwithstanding this the device forms a perfect seal.

5. The T-shaped rail *g* may be replaced by a flat rail or strip provided with bolts or the like projecting parts adapted to abut against the rails *e* when the sash *b*¹ or *i* is raised.

I claim:—

10. 1. In a threshold or sill, a lower sash, a strip fixedly attached to the lower rail of the said sash and a groove provided in the threshold or sill adapted to receive the said strip in the lower position of the said sash.

15. 2. In a threshold or sill, a lower sash, a strip fixedly attached to the lower rail of the said sash, a groove provided in the threshold or sill adapted to receive the said strip in the lower position of the said sash, and a second strip located in the said groove and adapted to shut the same.

20. 3. In a threshold or sill, a lower sash, a strip fixedly mounted to the lower rail of the said sash, a groove provided in the threshold or sill, a second strip seated in the said groove and means for yieldingly holding said second strip flush with the floor line.

25. 4. In a threshold or sill, a lower sash, a strip fixedly mounted to the lower rail of the said sash, a groove provided in the threshold or sill, a second strip seated in the said groove, means for yieldingly holding said second strip flush with the floor line, and locking means provided on the lower sash to hold the same in its closed position.

30. 5. In a threshold or sill, a lower sash, a strip fixedly mounted to the lower rail of the said sash, a groove provided in the threshold or sill, a second strip seated in the said groove and means positioned in the groove and acting against said second strip to hold the same yieldingly flush with the floor line.

35. 6. In a threshold or sill, a lower sash, a strip fixedly mounted to the lower rail of the said sash, a groove provided in the threshold or sill, a second strip seated in the said groove and a plurality of springs acting against said second strip to hold the same yieldingly flush with the floor line.

40. 7. In a threshold or sill, a lower sash, a strip fixedly mounted to the lower rail of the said sash, a groove provided in the threshold or sill, two strips attached to the threshold or sill and forming the said groove between them, a T-shaped strip seated in the said groove and means for yieldingly holding said T-shaped strip flush with the floor line.

45. 8. In a threshold or sill, a lower sash, two strips fixedly attached to the threshold or sill and forming a groove between them, a strip fixedly attached to the lower rail of the said sash and adapted to engage into the said groove, a second strip seated in the said groove, a plurality of cases or tubes arranged beneath the said groove, and springs within

said cases or tubes acting against said second strip to hold the same yieldingly flush with the floor line.

50. 9. In a threshold or sill, a lower sash, two strips attached to the threshold or sill and forming the groove between them, a strip fixedly attached to the lower rail of the said sash and adapted to engage into said groove, a plurality of cases or tubes positioned below said strips forming the groove, 75 slots provided in said cases or tubes, a second strip seated in the said groove and in the said slots, and springs within said cases or tubes acting against said second strip to hold the same yieldingly flush with the floor 80 line.

In testimony whereof I have hereunto set my hand.

HERMANN KAMPES.
